KNOCKDOWN BOX OR CRATE

Arthur C. Friedel, Syracuse, N. Y., assignor to
 J. F. Friedel Paper Box Company, Syracuse,
 N. Y., a corporation of New York

Application February 28, 1938, Serial No. 193,051

1 Claim. (Cl. 217—69)

This invention relates to improvements in a knockdown box or crate adapted to be used more particularly for the reception, for transportation or storage, of various dry products such as parts or units of a manufactured article, pieces of waste material, or refuse et cetera.

The invention pertains more particularly to a receptacle, often called a stacker-basket, of the class disclosed in my United States Letters Patent No. 1,220,621, issued March 27, 1917. The structure shown in this patent comprises a top frame, a bottom frame, corner posts and side panels all of which are releasably secured together to form a box or crate by tie-rods connecting corresponding corners of the top and bottom frames. The crate or stacker-basket thus constructed is not only comparatively inexpensive but is light, strong and durable so that the same may be easily moved from place to place. Furthermore the tie-rods are secured in operative relation with the top and bottom frames by suitable nuts so that the crate or basket may be quickly and easily collapsed into a relatively small, compact bundle or package for economy in shipment or storage when empty.

It has been found that when the top and bottom frames have the side rails and corner plates constructed and secured together in the manner shown and described in my Patent No. 1,220,621 mentioned above, the side rails frequently become loose in the corner plates and are often disconnected therefrom and thus render the stacker-basket or crate of little use before the sides and bottom members are worn out.

The main object of this invention is to provide top and bottom frames for a knockdown box, crate or stacker-basket of an improved construction without appreciably increasing the cost or labor of its construction whereby the life and usefulness of the frames and therefore of the box or crate is greatly increased.

A more specific object of the invention is to provide the corner plates and the rails with ribs and recesses extending transversely of the rails adapted to co-operate with each other for fixedly holding the rails against outward longitudinal movement with respect to the corner plates after said rails and corner plates have been assembled together.

I attain these objects by the structure illustrated in the accompanying drawing in which:

Figure 1 is a perspective view of a box or stacker-basket embodying the features of this invention.

Figure 2 is an exploded perspective view illustrating a corner post, a side panel, a bottom member and the side rails of the top and bottom frames adjacent said post, portions of said members being broken away and in section.

Figure 3 is a detail horizontal sectional view taken substantially in the plane of line 3—3, Figure 1, a corner portion of the bottom member being broken away.

Figure 4 is a vertical sectional view partly broken away taken on line 4—4, Figure 3.

Figure 5 is a detail transverse vertical sectional view taken on line 5—5, Figure 3.

Figure 6 is a perspective view of one of the corner plates.

The box or stacker-basket illustrated in the drawing is a substantially rectangular member and comprises similar top and bottom frames 1 and 1', four corner posts 2, side panels 3, and a bottom member 4. The side panels 2 and bottom 4 are preferably composed of pasteboard, a pressed wood composition such as that sold under the trade name of Masonite, or equivalent comparatively light, strong, and inexpensive material.

The top and bottom frames 1 and 1' are substantially identical in size and construction. Each of these frames consists of a plurality of, in this instance four, similar rails 6 one for each side of the box and four metal corner plates 7 for connecting or coupling the adjacent ends of the rails together and also for coupling the corners of such frames to the adjacent ends of the corner posts 2.

The corner posts 2 and rails 6 are preferably made of relatively narrow strips of wood for lightness and cheapness of manufacture. The corner posts 2 are, as shown, angular in cross-section to provide substantially rectangular recesses 8 extending longitudinally of the posts for the reception of adjacent vertical edges of the side panels 3.

The rails 6 are provided with length-wise channels 9 extending from end to end in one side thereof for receiving the adjacent longitudinal edges of the side panels 3 whereby the side portions of the rails adjacent said channels will maintain the panels against inward and outward deflection.

The lengths of the corner posts 2 are preferably substantially equal to the height of the box so as to extend from the plane of the upper surfaces of the side rails 6 of the top frame 1 to the plane of the lower surfaces of the rails 6 in the bottom frame 1' as illustrated in Figure 4,

while the vertical width of the side panels 3 are slightly less than the length of the posts 2 to engage in the channels 9 when the ends of the posts abut against the corner plates 7 of the top and bottom frames.

The corner plates 7 as previously stated are made of metal, preferably wrought-iron, and are angular in top plan to correspond to the angles of the corner of the box. These corner plates 10 and frames are substantially identical and interchangeable. Each plate is provided with arms 10 extending, in this instance, at right angles to each other. Each arm is provided with inner and outer side walls or flanges 11 and 11' extending outwardly from one side thereof substantially normal thereto and which provide channels 12 extending inwardly length-wise of the arms from the outer ends thereof. These channels are of substantially the same width as 20 the side rails 6 to receive the corresponding end portion of the adjacent side rails therein. The side of each plate from which the walls 11 and 11' extend is formed with a rectangular socket 13 intermediate channels 12 and which is defined from said channels by ribs or braces 14 formed integral with the inner and outer side walls or flanges 11 and 11' for the reception of an end of a corresponding corner post 2.

Portions of the inner and outer side walls or flanges 11 and 11' are elongated transversely to form gripping fingers 15 of greater length or depth from the base of the corresponding arms 10 than the thickness of the portions of the rails 6 to be received in the channels 12, so that, when 30 the rails are placed in their respective channels 12 with one side resting against the base of the corner plate, the portions of the gripping fingers 15 which project beyond the opposite sides of the rails may be bent over and upon such sides, as 35 illustrated in Figure 3, so as to firmly hold the rails in contact with the base of the plate.

The construction thus far defined is substantially the same as that shown and described in my above mentioned Patent No. 1,220,621 and the 40 novel features of this invention will now be described.

In order that the rails 6 will be fixedly held in their respective channels 12 against outward lengthwise movement from beneath the gripping fingers 15 I have provided each arm 10 of the corner plates with a rib 17 formed integral therewith and which extends transversely through the corresponding channel 12 intermediate the ends thereof between the side walls 11 and 11', as 50 illustrated in Figure 6. Each rail 6 is provided with a pair of grooves 18 in the side thereof opposite the channels 9. These grooves 18 extend transversely of the rails and are adapted to receive a corresponding rib 17 therein when said 55 end of the rails is secured in the corresponding channel 12 by the gripping finger 15. The grooves 18 are spaced from the adjacent ends of the rails 6 a distance substantially equal to the distance between a rib 17 and the adjacent side of the 60 corresponding socket 13 so that, when the rails are secured in their respective channels 12, the ends thereof will register with the adjacent sides of the corresponding sockets 13 and abut against the adjacent edge of the corner post received in 65 said socket and tend to stiffen the entire frame when the corner plates 7 and corner posts 2 are assembled in operative relation with each other.

In order that the ends of the rails 6 may abut firmly against the adjacent edges of the corner 70 posts 2 the rails are provided with the usual

transverse rabbets or recesses 20 at the ends thereof to receive the ribs 14.

In forming either the top or bottom frames a plurality of rails 6, corresponding in number to the sides of the box, are placed with their ends in the channels 12 of a corresponding number of corner plates 7. These corner plates are supported upon a flat surface and the rails are positioned with the grooves 18 receiving corresponding ribs 17 which automatically positions the adjacent ends of the rails in proper aligned relation with the corresponding socket 13 so that when the frame is assembled with the corner posts 2 of said ends of the side rails will abut against the adjacent edges of the corner posts. 15 The outer ends of each pair of gripping fingers 15 are next bent inwardly toward each other and upon the adjacent side of the rails opposite that which rest upon the base of the corner plates. This bending operation of the gripping fingers 20 serves to tightly clamp the wood rails to the corner plates and to co-operate with the ribs 17 for fixedly securing the rails and plates to each other without the use of nails, screws or other fastening means. It is thus seen that each bottom 25 and top frame is a substantially rigid member and comprises only a plurality of side rails, depending in number upon the number of sides of the box, and the corresponding number of corner plates 7.

The top and bottom frames are assembled in 30 the conventional manner with the side panels 3 by first placing the bottom frame upon a suitable support with the channels 9 of the side rails facing upwardly. The corner posts 2 and the side panels 3 are then placed in position with the lower ends 35 of the posts resting in the sockets 13 of the bottom frame and the lower longitudinal edges of the side panels resting in the corresponding channels 9, while the vertical side edges of the panels are seated in the recesses 8 provided in the inner 40 sides of the corner posts.

The upper frame is next assembled with the posts and side panels with the upper ends of the posts registering in the sockets 13 thereof and with the upper longitudinal edges of the side 45 panels 3 registering in the corresponding channels 9. The lower and upper frames are then firmly drawn against the ends of the posts by means of tie-rods 21 passing through apertures 50 formed in the bases of the corner plates 7, each rod being provided with a head 23 at one end and at its other end with an internally threaded sleeve or nut 24. Each nut or sleeve 24 may, as shown, be provided with a slot 25 for the reception of a screw-driver by which it may 55 be turned upon the adjacent threaded end of the main portion of the tie-rod.

The apertures 22 in the corner plates 7 are so arranged as to register with the recesses 8 of adjacent posts. These apertures are so spaced 60 from the outer corners of the sockets 13 that the tie-rods will be sufficiently spaced from the bases of the recesses 8 to receive the vertical edges of the panels 3 therebetween, as illustrated more particularly in Figure 3. It is thus seen that 65 the tie-rods 21 not only serve to securely clamp the top and bottom frame, corner posts and side panels to each other, but also co-operate with the corner posts for maintaining the vertical edges of the side panels against lateral deflection. 70

The outer faces of the bases of the corner plates 7 may, as shown, be provided with raised bosses 75 which surround the corresponding apertures 22, said bosses being provided with sockets in which the adjacent heads of the tie-rods are 80

- seated and protected by the outer flanges of the bosses. The bosses 26 on the bottom frame not only provide feet for the box, but may be, as shown, of greater diameter than the bosses on the corner plates of the top frame so that when the boxes are stacked one upon the other they will telescope the boss of the upper frame to hold the stacked boxes in vertical alignment, as indicated by broken lines in Figure 4.
- 5 The bottom 4 may as indicated be formed of a single piece of suitable material such as cardboard and is of substantially the same area as the interior of the box. This bottom member may be inserted in the box just prior to the 10 mounting of the top frame upon the posts 2 and the side panels 3. The bottom 4 is positioned with the marginal edges thereof resting upon the inner adjacent surfaces of the side rails 6 of the bottom frame.
- 15 The parts of the box may be readily collapsed by simply detaching the nuts 24 from the tie-rods and then withdrawing said rods, whereupon the upper frame, corner posts, and side panels may be separated one from each other and from the 20 bottom frame and all of these parts may be laid flatwise upon the bottom frame within a relatively small space, or, if necessary, the rails of both frames may be detached from the corner plates 25

by simply loosening the gripping fingers 15 and then withdrawing the rails from the respective channels.

I claim:

In an end frame of a knockdown box or crate, 5 a set of rails one for each side of the frame, and corner plates for coupling adjacent ends of the rails to each other, each of said corner plates comprising arms arranged in angular relation to each other, each arm having inner and outer side 10 walls extending laterally from one side thereof in spaced relation to each other to form a channel receiving the adjacent end of the corresponding rail, said side walls having extensions at the upper or free edges thereof bent inwardly toward each other providing gripping fingers frictionally 15 engaging adjacent portions of the bar, said arms also having upstanding projections rising from the plane of the bottom wall thereof and in the vertical plane of the gripping fingers extending 20 into the corresponding channels, said rails having grooves in one side thereof receiving a corresponding arm projection therein for maintaining the rails against longitudinal movement in said channels with respect to the corner plate and to 25 each other.

ARTHUR C. FRIEDEL.
